UNITED STATES PATENT OFFICE

FAY D. KINNEY, OF WENHAM, MASSACHUSETTS, ASSIGNOR TO UNITED SHOE MANUFACTURING CORPORATION, OF PATERSON, NEW JERSEY, A CORPORATION OF NEW JERSEY

METHOD OF ASSEMBLING THE UPPERS OF RUBBER SHOES

Application filed January 23, 1929. Serial No. 334,551.

This invention relates to a method of assembling parts of rubber shoes to form closed uppers, the term "rubber shoes" being intended to cover those shoes and overshoes commonly made in rubber factories which require vulcanization.

In the manufacture of a rubber shoe it is customary, in some cases, to assemble certain parts of the shoe to form a closed upper, 10 to mount the closed upper together with an insole upon a last, to last the margin of the upper over upon the insole, to attach the outsole and then to subject the shoe to vulcanization, the general object of the present 15 invention being to facilitate the rapid and accurate assembling of the upper for the purpose described.

In one aspect the invention provides a method of assembling parts of a rubber shoe 20 to form a closed upper which comprises mounting certain parts upon one section of a suitable form, mounting other parts upon another section, putting the sections together and thereby uniting parts on one section with 25 parts on the other, and then removing the assembled parts from the form. The illustrated method is concerned with the assembling of the upper of an arctic or so-called "gaiter" wrong side out. In carrying out 30 the method the vamp foxing and the vamp are mounted upon a generally wedge-shaped section of the form, portions of the opposite edges of the vamp being bent over upon a flat face of the section and fastened 35 in place by a piece of tape. The quarter foxing and the quarter are mounted upon the other section of the form, portions of the opposite edges of the quarter being bent over upon a flat face of the second section and fastened 40 in place by a second piece of tape. The sections are then pressed together with their flat faces opposed to each other, this pressure serving through the pieces of tape, to unite the bent-over portions of the vamp and quarter. 45 Certain stays may then be applied after

which the lining is wrapped about the form over the parts which have already been assembled thereon. The upper at this stage has been completely assembled wrong side out upon the form with certain parts gripped 50 between the adjacent flat faces of the sections. In order to remove the upper from the form the wedge-shaped section is pulled out so as to give access to the pieces of tape referred to above. These pieces are then 55 cut and the upper removed from the other section. The upper is then turned right side out.

Referring now to the accompanying drawings Fig. 1 is a perspective of the closed upper of a ladies' arctic or so-called "gaiters", 60 part of the lining having been broken away;

Fig. 2 is a perspective of the sections of the sectional form in separated relation with certain parts of the upper mounted upon the 65 sections;

Fig. 3 is a perspective of the form with certain parts mounted upon it, after the sections have been put together; and

Fig. 4 is a plan of a lining which is the last 70 part of the upper to be put in place upon the form.

Referring first more particularly to Fig. 1, the closed upper of the particular rubber shoe shown comprises a vamp 1 and a quarter 3 75 fastened together at two generally triangular localities 5. The upper portion of the quarter 3 has an ornamental pattern and, in the finished shoe, is bent down to form a so-called cuff. Along the bottom of the vamp is the 80 vamp foxing 7; and along the bottom of the quarter is the quarter foxing 9. On the inside of the vamp and quarter are two generally triangular stays 11, these stays being in the localities which are folded in the finished 85 shoe to form the bellows of the arctic. A lining 13 covers the entire inside of the vamp and quarter except, of course, the ornamental cuff portion of the quarter.

For the assembling of the parts of this up- 90

per there is provided a form consisting of two sections 15 and 17 which will be termed respectively the vamp section and the quarter section. The vamp section 15 is generally ⁵ wedge-shaped, being wider at the top than at the bottom; and, extending from top to bottom, is a flat face 19 provided with a groove 21. The sides 23 are substantially flat throughout most of their extent and merge ¹⁰ into a curved face 25. The quarter section has comparatively narrow ends and a wider middle portion. The sides 27 are substantially flat throughout most of their extent and merge ¹⁵ into two curved faces 29 which meet at 31. This section has a flat face 33 corresponding to the flat face 19 of the vamp section, and is provided with projections 35 which fit into the groove 21 so that the sections may be slidably connected. The two ²⁰ ~~and~~ ²¹ projections 35 are provided with small holes 37, 39 which, when the sections are together register respectively with small holes 41, 43 in the vamp section 15 to receive pins so that the sections may be accurately brought ²⁵ together always in the same relation to each other.

The vamp section is provided with a socket ⁴⁵ and a pin 47; and the quarter section is provided with a similar socket 49 and pin ⁵⁰ 51. Although the method of assembling the parts of the upper may be practiced by hand and will be so described, certain of the parts of the upper may, if desired, be mounted upon the sections of the form or upon the complete ⁵⁵ form by means of a machine, not herein shown, but of the type of the lining mounting machine disclosed in application Serial No. 309,181 filed Sept. 29, 1928 in my name. In machines of this type the lining or other shoe ⁶⁰ part is laid flat upon a strap, said strap being yieldingly held taut in horizontal position over two presser rollers which are yieldingly held close together but may be forced apart. The form, or one of the sections, is detachably mounted above the strap upon a cross-head in a substantially horizontal position with the curved face downward; and then the cross-head is moved down whereupon the form, or the section, as the case may be, ⁶⁵ pushes the shoe part and the strap down between the rollers so that the shoe part is wrapped about the curved face and sides of the form and pressed into place. The sockets 45, 49 and pins 47, 51 are provided for ⁷⁰ the purpose of detachably mounting either section or the complete form upon the cross-head referred to above whenever it is desired to do so.

In assembling the parts of the upper, the ⁷⁵ vamp foxing 7 is mounted upon the vamp section 15 of the form in the position shown in Fig. 3. This foxing is made of unvulcanized rubber and hence will adhere to the form sufficiently to retain its position. The ⁸⁰ vamp 1 is next mounted upon the section

⁷⁰ 15 in the manner shown so that it somewhat overlaps the foxing 7, the opposite edges of the upper portion of the vamp being bent over upon the flat face 19 and fastened together by a piece of tape 53 which is adhesive upon both sides. The quarter foxing 9 is mounted as shown upon the section ⁷⁵ 17 with its ends projecting somewhat beyond the flat face 33. The quarter is then mounted in the manner shown so that it somewhat overlaps the foxing 9, the opposite edges near the top being bent over upon the flat face 33 and fastened together by a piece of tape 55. It will be understood that the sections of the form may have marks ⁸⁰ upon them to facilitate the proper location of the various parts of the upper.

⁸⁵ The sections of the form are now pressed together with the projections 35 extending into the groove 21 and the flat faces 19 and 33 substantially in contact, as shown in Fig. 3. When the sections are thus pressed together, the two pieces of adhesive tape 53, 55 are caused to adhere to each other as well as to any portion of the vamp or quarter with which they come in contact, the result being that the vamp and quarter are united in the localities indicated at 5 in Fig. 1. In order to strengthen this union between the vamp and the quarter as well as to provide a stronger bellows in the finished shoe, two triangular stays, one of which is shown at 11, are now applied, each stay extending partially over the quarter and partially over the vamp. The ends of the ⁹⁰ quarter foxing 9 are lapped over upon the vamp foxing 7, trimmed, if necessary, and pressed into place.

⁹⁵ If the vamp and the quarter are made of suitable laminated sheet material, the assembled upper may now be complete, but usually a lining is used. Such a lining of friction fabric is shown in Fig. 4. This lining is wrapped about the form and the parts of the upper already mounted upon it as they appear in Fig. 3, the margins of the free edges 57, 59 of the lining being brought together at the rear of the form and then trimmed.

¹⁰⁰ The upper, at this stage, has been completely assembled wrong side out upon the form. In order to remove it from the form, the wedge-shaped section 15 is pulled out so as to give access to the interior of the upper. The tapes 53, 55 are then severed and the upper thus freed from the other section of the form. The upper is then turned right side out and is ready to be used, as has been outlined above, in the manufacture of a rubber shoe.

¹⁰⁵ Having thus described my invention, what I claim as new and desire to secure by Letters Patent of the United States is:

1. The method of assembling parts of a rubber shoe to form a closed upper which

comprises mounting certain parts upon one section of a form, mounting other parts upon another section, putting the sections together and thereby uniting parts on one section with parts on the other section, and removing the assembled parts from the form.

2. The method of assembling parts of a rubber shoe to form a closed upper which comprises mounting parts of the forward portion of the upper upon one section of a form, mounting parts of the rear portion of the upper upon another section, putting the sections together and thereby uniting parts on one section with parts on the other, and removing the assembled parts from the form.

3. The method of assembling parts of a rubber shoe to form a closed upper which comprises mounting parts of the forward portion of the upper upon one section of a form, mounting parts of the rear portion of the upper upon another section, putting the sections together and thereby uniting parts on one section with parts on the other, wrapping a lining about the parts on the form, and removing the assembled parts from the form.

4. The method of assembling parts of a rubber shoe to form a closed upper which comprises mounting separate parts of the upper upon the respective sections of a sectional form, putting the sections together and thereby uniting parts on one section with parts on the other, pulling out one of the sections to gain access to the inside of a portion of the upper, and freeing the upper from the other section.

5. The method of assembling parts of a rubber shoe to form a closed upper which comprises mounting parts of the forward portion of the upper upon a generally wedge-shaped section of a sectional form including fastening opposite edges of one of the parts, mounting the parts of the rear portion of the upper upon another section of the form including fastening opposite edges of one of said last-named parts, putting the sections together and thereby uniting parts on one section with parts on the other, pulling out the wedge-shaped section, severing the fastening means, and removing the assembled upper from the other section.

6. The method of assembling parts of a rubber shoe to form a closed upper which comprises mounting the parts of the forward portion of the upper upon a generally wedge-shaped section of a sectional form including fastening together the opposite edges of one of the parts by a piece of sheet material, mounting the parts of the rear portion of the upper upon another section of the form including fastening together opposite edges of one of the parts by a second piece of sheet material, putting the sections together and thereby uniting parts on one section with parts on the other, pulling out the wedge-

shaped section, severing the pieces of sheet material and removing the assembled upper from the other section.

7. The method of assembling parts of a rubber shoe to form a closed upper which comprises mounting the vamp and its associated parts upon a generally wedge-shaped section of a sectional form including fastening opposite edges of the vamp by a piece of adhesive tape, mounting the quarter and its associated parts upon another section of the form including fastening opposite edges of the quarter by a piece of tape, putting the sections together and thereby uniting the vamp to the quarter, pulling out the wedge-shaped section to give access to the tape, severing the tape, and removing the assembled upper from the other section.

8. The method of assembling parts of a rubber shoe to form a closed upper which comprises mounting the vamp and associated parts upon a generally wedge-shaped form having a face provided with a guideway including bending opposite portions of the vamp over upon said face and fastening them together, mounting the quarter and associated parts upon another section of the form having a face provided with a guide adapted to enter the guideway, said mounting including bending opposite portions of the quarter over upon the last-named face and fastening them together, pressing the sections together with the guide in the guideway whereby the vamp and quarter portions of the upper are united, pulling out the wedge-shaped section, cutting the fastening means, and removing the assembled part from the other section.

9. A method of assembling parts of a rubber shoe to form a closed upper which comprises mounting shoe-upper parts on a substantially wedged-shaped section of a form, mounting other parts upon another section of the form, putting the two sections together to complete the form and uniting parts on one section with parts on the other section, and thereafter removing first the substantially wedged-shaped section of the form and then the other section of the form from within the shoe upper.

10. A method of assembling parts of a rubber shoe to form a closed upper which comprises mounting the vamp portion of the upper on a substantially wedged-shaped section of a form, mounting the quarter portion of the upper upon another section of the form, putting the sections together to complete the form and uniting the shoe parts on the two sections, and thereafter removing first the substantially wedged-shaped section and then the other section of the form from within the shoe upper.

11. A method of assembling parts of a rubber shoe to form a closed upper which comprises mounting parts of the vamp portion of the upper upon a substantially

wedged-shaped section of the form, mounting parts of the quarter portion of the upper upon another section of the form, putting the sections together to complete the form and uniting parts on one section with parts on the other, wrapping a lining member about the parts of the form, and thereafter removing first the substantially wedged-shaped section and then the other section of the form from within the shoe upper.

In testimony whereof I have signed my name to this specification.
